DESIGN FOR A PLUG VALVE BODY

Sven J. Nordstrom, Piedmont, Calif., assignor to
Merco Nordstrom Valve Company, Pittsburgh,
Pa., a corporation of Delaware

Application July 9, 1935, Serial No. 57,575

Term of patent 14 years

To all whom it may concern:

Be it known that I, Sven J. Nordstrom, a citizen of the United States, residing at Piedmont, in the county of Alameda and State of California, have invented a new, original, and ornamental Design for Plug Valve Bodies, of which the following is a specification, reference being had to the accompanying drawing, forming part thereof.

Figure 1 is a perspective view of a plug valve body, showing my new design.

Figure 2 is a side elevational view of the valve body of Figure 1; and

Figure 3 is a top plan view of the valve body of Figure 1.

I claim:

The ornamental design for a plug valve body, substantially as shown.

SVEN J. NORDSTROM.
